REFRIGERATING APPARATUS

Filed Sept. 30, 1929

UNITED STATES PATENT OFFICE

HARRY F. SMITH, OF DAYTON, OHIO, ASSIGNOR TO FRIGIDAIRE CORPORATION, OF DAYTON, OHIO, A CORPORATION OF DELAWARE

REFRIGERATING APPARATUS

Application filed September 30, 1929. Serial No. 396,230.

This invention relates to refrigerating apparatus and more particularly to devices for automatically controlling refrigerating systems, especially those of the intermittent absorption type.

5 One of the objects of the invention is to provide an improved control apparatus which permits the refrigerating system to operate only in response to an adequate flow of cooling medium.

10 Another object is to provide a control apparatus in which the existence of a vacuum is essential to operation of the refrigerating system, and to provide an improved arrangement for maintaining a vacuum.

15 More specifically, it is one of the objects of the invention to provide an arrangement in which a dependable control of the vacuum system can be maintained even with low rates 20 of flow of cooling medium.

Further objects and advantages of the present invention will be apparent from the following description, reference being had to the accompanying drawing, wherein a preferred form of the present invention is clearly shown.

The single figure of the drawing is a diagrammatic representation of a refrigerating system embodying the invention.

As represented therein, the improved refrigerating system includes a generator-absorber generally designated by 50 which is automatically heated and cooled to supply refrigerant to a refrigerating element or evaporator 52 and to withdraw refrigerant from the element, which may be used to cool any suitable cabinet or compartment 54. A condenser 56 is interposed between the generator-absorber and the refrigerating element. The generator-absorber 50 includes any suitable container 58 for absorbent which is connected by a refrigerant conduit 60 with the chamber 56 of the condenser which is cooled in any suitable manner for example by water or other cooling medium flowing through a coil 62. Liquefied refrigerant flows from the chamber 56 through a conduit 64 to the evaporator 52. When the generator-absorber is heated, gaseous refrigerant is given off, and will flow to and be

condensed in the coldest part of the system. If the evaporator has previously been cooled by evaporation of refrigerant produced by an absorbing period, it will be colder than the condenser, hence refrigerant will tend to 55 liquefy in the evaporator. In order to reduce the amount of condensation which can take place in the evaporator, the latter is formed as an insulated reservoir of small surface 66 having depending circulating and evaporating tubes 68 of large exposed surface which are maintained at all times filled with liquid refrigerant. Since the evaporating tubes are filled with liquid and since the reservoir is insulated, the heat of condensation of the refrigerant initially condensed will be confined to the reservoir and will speedily elevate its temperature above that of the condenser after which all condensation will take place in the condenser. 60 The warm liquid will remain at the top of the evaporator and will not circulate. When the generator-absorber is cooled, the refrigerant in the reservoir will be evaporated, reducing the temperature of the reservoir to 65 that of the tubes 68, after which continued cooling of the generator-absorber will produce evaporation in the tubes which are exposed to the atmosphere to be cooled. 70

A closed vapor circuit is provided for the 80 purpose of heating and cooling the generator-absorber 58. The latter is enclosed in a container 70 herein termed a vapor shell which may be filled to an upper level 72 with volatile liquid such as alcohol or ethyl chloride and which is connected to a vapor condenser 74 above the level of the vapor shell by means of a vapor conduit 76-78 leading from the top of the vapor shell to the top of the condensing chamber, and a liquid conduit 85 80 leading from the bottom of the condensing chamber 74 to a point near the bottom of the container 70. The liquid in the vapor shell is vaporized by any suitable heating device herein exemplified as a gas burner 82 placed beneath the vapor shell. When the generator-absorber is to be heated the burner is lighted by automatic control means herein-after described in detail and a valve 84 is 90 closed in a valve chamber 86 interposed be- 95 100

between the sections 76 and 78 of the vapor conduit. When the burner begins to vaporize the liquid in the chamber 70, the pressure of the vapor forces the remaining liquid up 5 through the conduit 80 filling the condensing chamber 74 and reducing the level of the liquid in the chamber 70 to a point which may be below the generator-absorber 58 and is exemplified by the level 88. The liquid continues 10 to be vaporized by the burner and condensed on the generator-absorber 58 giving up its latent heat and causing the absorbent to evolve its refrigerant.

The vapor condenser may be cooled by any 15 suitable circulating medium such as water which preferably flows continuously through a coil 90. When the generator-absorber is to be cooled the burner is turned off and the valve 84 in the vapor conduit is opened. This permits the vapor in the vapor shell to 20 pass into the vapor condenser and the liquid in the condenser to flow down into the container 70, again submerging the generator-absorber to the level 72. The hot generator-absorber vaporizes the liquid, the vapor flowing 25 up through the conduit 76 to be condensed again. This vaporization and condensation of the circulating liquid cools the generator-absorber to withdraw and absorb the refrigerant from the evaporator 52.

The invention contemplates suitable automatic control devices for cyclically heating and cooling the generator-absorber in response to the refrigerating demand or the 30 conditions within the system. Preferably the cooling water circulates continuously through both the refrigerant condenser and the vapor condenser since at any instant one of the other of the condensers must be cooled, and since the circulation of water through 35 either condenser does no harm when that condenser is not functioning as such. Water may enter the system at the refrigerant condenser cooling coil 62 and flow by a conduit 40 92 to the vapor condenser cooling coil 90.

In order to obtain the necessary power for actuating the control devices a jet or entrainment pump is placed in the water conduit 92. This pump includes a chamber 94 having a 45 restriction or throat 96 into which a jet of water is discharged from an orifice 97. Connected to the chamber 94 is a suction conduit system 98 in which a vacuum is maintained by the jet pump. Connected to the conduit 98a is an expansible chamber motor 100 which is preferably formed of a bellows, the interior of which is connected with the conduit 98a but which is otherwise sealed from the atmosphere. The bellows may be expanded 50 by a spring 102 when the pressure in the conduit 98 is not reduced, and may be collapsed by atmospheric pressure when a vacuum exists in the conduit. The end of the bellows is attached by a pin and slot connection to a lever 104 provided with a fork 106

which is pivoted at 108. Between the forks a portion 110 of the lever extends within the casing 86 for opening the valve 84, the lever being sealed to the casing by a flexible connection formed by a packing bellows 112 placed within the fork 106 and surrounding the portion 110 and sealed thereto. When a vacuum exists in the conduit 98, the bellows 100 collapses to close the valve 84, and when the vacuum is broken, the bellows expands to 70 open the valve.

The pivots 108 of the forked lever 104 are mounted on a second forked lever 114, pivoted at 116 and also surrounding the packing bellows 112, which may expand and contract 80 with changes of pressure in the valve casing 86. The fork 114 may move up and down about the pivot 116 and is urged against a stop 118 by a spring 120. The fork 114 has an arm 121 extending to the left of the pivot 85 through which freely passes a valve stem 122 carrying a vacuum-breaking valve 124 which may co-operate with a seat 126 to close the vacuum conduit system from the atmosphere. The valve may be closed by downward 90 movement of the arm 121 when the packing bellows collapses due to low pressure in the valve casing 86. The valve may be opened by upward movement of the arm 121 when the packing bellows expands due to high 95 pressure. A light spring 128 is interposed between the arm 121 and the valve stem to raise the valve away from its seat once it has been opened.

The gas burner 82 is controlled by a gas valve 130 attached to a bellows 132, similar to the bellows 100, which is also connected to the vacuum conduit system 98 and is collapsed to open the gas valve when the vacuum is produced and is expanded to close the gas valve when the vacuum is broken. The burner is lighted when the valve is open from a constantly burning pilot 134. The vacuum conduit system includes a high temperature safety conduit 136, the end of which is normally closed by a fusible plug 140 disposed in a well in the vapor shell 70. This is for the purpose of breaking the vacuum to shut off the burner in case of an excessively high temperature in the vapor shell.

It will be appreciated that the rate at which refrigeration is evaporated depends on the rate of absorption by the absorber 58, which in turn depends upon the rate at which the absorber is cooled. This of course is directly dependent upon the temperature and rate of flow of cooling water. Consequently the rate at which refrigeration is produced can be controlled directly by controlling the flow of cooling water. For this purpose a valve casing 142 containing a throttle valve 144 is interposed in the conduit 92. This valve is actuated by a lever 146 pivoted at a stationary point 148, sealed to the casing by a packing bellows 150 and urged counter- 110 115 120 125 130

clockwise by the spring 152 which serves to open the valve. The maximum opening of the valve is determined by an adjustable stop 154. The lever 146 is rotated clockwise to 5 throttle the water in response to the temperature of the evaporator by means of a bellows 156 which is connected to the conduit 64 by a conduit 158. The pressure of the evaporator and consequently the pressure in the 10 bellows 156 is a function of the temperature of the evaporator. Consequently when the evaporator has been reduced to the desired temperature the bellows 156 collapses to 15 throttle the supply of cooling water which slows down the refrigeration rate to that required to maintain the desired temperature. If refrigeration at a greater rate is demanded the evaporator tends to become warm and its pressure is increased permitting the bellows 20 156 to expand somewhat and permitting the valve to open to produce absorption at a increased rate.

Preferably the throttle valve operates in the jet orifice 97, and is provided with a cylindrical jet-directing member 157 which projects thru the orifice and directs the jet of water into the throat 96.

The temperature at which the cabinet will be maintained can be adjusted by regulating 25 the temperature at which the valve 144 will be actuated and the amount of movement of this valve. This can be accomplished by adjusting the tension of the spring 152, but I prefer to provide an independent cold control 30 in the form of the separate spring 160 which may be brought into play when desired to resist the movement of the control lever 146 and the tension of which may be suitably adjusted by any convenient mechanism 35 such as the cam 162 operated by the lever 164. In this manner the spring tension on the lever 146 may be simply adjusted, and yet the normal adjustment, that is the tension of the spring 152, will remain undisturbed when the cold control adjustment is 40 removed.

Since the vacuum conduit system 98 is normally closed to the atmosphere when the pressure responsive devices 100 and 132 are to be 45 actuated, the jet pump will soon exhaust the system of air. When this condition occurs there is practically no air entrained by the jet and the surface of the jet becomes very smooth. Difficulty is experienced in keeping 50 a perfectly smooth jet continuously in contact with the wall of the throat 96 because the jet may be so attenuated, or may become so small due to low water pressure that it may 55 not fill the orifice or throat. Also the jet may be deflected by minute particles of foreign matter or by the misalignment of the valve 144, or the water pressure may drop to a value 60 which makes it difficult to keep the throat 65 filled. In any of these contingencies air may

leak back through the throat 96 and destroy the vacuum in the conduit system 98.

To avoid the possibility of these difficulties I provide means for admitting a limited quantity of air to the jet after the pressure in the vacuum conduit system has been reduced to the value necessary to actuate the bellows 100 and 130. Within the scope of this invention, the air may be introduced into the water stream before it reaches the jet pump as by aerating the water supply, but for the sake of simplicity I prefer to admit air directly to the chamber 94 around the jet. This may be accomplished by a check valve 70 having a restricted opening 166 which may admit air to the vacuum conduit system, and hence eventually to the chamber 94, by means of the conduit 168, the orifice 166 being normally closed by a valve 170 which is loaded 75 to the extent necessary to maintain the valve closed until the desired low pressure is attained. The loading may be accomplished 80 by a spring or any other suitable loading device. As illustrated for the sake of simplicity, the valve is a heavy weight the end of 85 which is formed into the valve proper. Preferably the valve is pointed to provide a projection which extends thru the opening 166 when the valve is closed for the purpose of 90 removing any dust which may accumulate in the opening. Thus every time the burner 82 is turned off the valve 170 will drop and its point will assure that the opening 166 is 95 clean.

The provision of the valve 170 has an additional advantage that the degree of vacuum maintained in the vacuum conduit system is just sufficient to insure operation of the bellows. The size of the opening 166 and the weight of the valve 170 are so proportioned 100 that air can not be admitted to the system fast enough to increase the pressure above that required to collapse the bellows, but on the other hand it prevents the production of 105 an extremely high vacuum which might place 110 an unnecessary strain on the bellows.

Operation of the system

When the apparatus is first started the refrigerator cabinet is warm and the generator-absorber 58 is charged with refrigerant. The bellows 156 is expanded and the rod 146 consequently moved against the stop 154 by the spring 152 to permit the maximum flow 115 of water thru the condensing circuit. This flow produces a sufficiently low pressure in the conduit system 98 to collapse the valve bellows 100 and close the vapor valve to prevent the circulation of heating and cooling fluid. Simultaneously the gas valve bellows 132 is collapsed to open the gas line and supply the burner 82 which is lighted by the pilot 134.

Any further reduction in pressure in the 120 vacuum conduit system opens the valve 170 125

which prevents the production of low pressures and insures the maintenance of the bellows 100 and 132 in collapsed condition by supplying just sufficient air to the pump chamber 94 to keep the jet sufficiently turbulent to maintain the vacuum sealed. The liquid in the generator-absorber chamber 70 now stands at the level 72 but a small quantity of this liquid is soon vaporized and the remaining liquid forced thru the liquid conduit 80 into the condenser 74 where it remains inert. After all of the refrigerant has been driven out of the generator-absorber the pressure of the heating and cooling vapor increases, until at a predetermined high pressure the packing bellows 112 on the valve operating lever 104 expands against the force of the spring 120 to raise the arm 121 a sufficient amount to compress the spring 122 to open the vacuum breaking valve 124. Breaking the vacuum permits the two bellows 100 and 132 to expand, opening the valve 84 and closing the gas valve 82. As soon as the vacuum valve is open the spring 128 lifts the valve from its seat in order that subsequent contraction of the bellows will not immediately seat valve 124 but will permit it to remain open until a predetermined low pressure in the vapor circuit has been reached, this condition representing a predetermined low temperature of the generator-absorber.

This generator-absorber is now cooled by the circulation of fluid in the vapor circuit as has been previously described. As the cooling progresses the refrigerant evaporates in the evaporator and is absorbed in the generator-absorber. After all of the refrigerant has been taken up which the generator-absorber can absorb the latter suddenly tends to drop in temperature to the temperature of the cooling water. This reduces the pressure in the vapor cooling circuit sufficiently to contract the bellows 112 to close the vacuum valve 124 and initiate another generating period.

While the form of embodiment of the invention as herein disclosed constitutes a preferred form, it is to be understood that other forms might be adopted, all coming within the scope of the claims which follow.

What is claimed is as follows:

1. Apparatus of the character described comprising a normally closed pressure responsive actuator, means for reducing the pressure within the actuator including an orifice and means for discharging a jet of liquid into the orifice, and means for insuring continuous contact between the jet and a wall of the orifice including means responsive to a predetermined low pressure within the actuator for admitting gas to contact with the jet.

2. Apparatus of the character described comprising a normally closed actuator responsive to a predetermined low pressure for

moving a control device, means for reducing the pressure in the actuator to a predetermined degree including an orifice and means for discharging a jet of liquid into the orifice and means for insuring continuous contact between the jet and the wall of the orifice including means responsive to pressures in the actuator below said predetermined pressure for bringing a gas into contact with the liquid jet. 75

3. Apparatus of the character described comprising a normally closed actuator responsive to a predetermined low pressure, means for reducing the pressure within the actuator including an orifice and means for discharging a jet of liquid into the orifice, and means for insuring continuous contact between the jet and a wall of the orifice including a valve responsive to a pressure below said predetermined pressure in the actuator for admitting air to the jet. 85

In testimony whereof I hereto affix my signature.

HARRY F. SMITH.
